UNITED STATES PATENT OFFICE.

CHARLES W. GORMAN, OF MUSKOGEE, OKLAHOMA.

ELECTRIC SWITCH.

Original application filed April 2, 1925, Serial No. 20,255. Divided and this application filed June 30, 1927. Serial No 202,605.

This application is a division of my pending U. S. application Serial No. 20,255, filed April 2nd, 1925, on improvements in door-operating mechanisms.

5 The present invention relates to electrical switches of a type in which a traveling contact engages stationary contact means, and it is the object of such invention to provide a new and improved construction for the stationary contact means, permitting longitudinal adjustment thereof, so that the length of time which the traveling contact will remain engaged with the stationary contact means, may be varied as desired. The invention is 10 intended primarily for use with door operating mechanisms, such as that shown by the parent application above referred to. However, it is not restricted to this particular field of use.

20 Fig. 1 of the accompanying drawing, is a side elevation partly broken away and in section, showing a switch embodying my invention.

Fig. 2 is a horizontal sectional view as indicated by line 2—2 of Fig. 1.

Figs. 3 and 4 are vertical transverse sections on the correspondingly numbered lines of Fig. 1.

In the drawings above briefly described, the 30 numeral 5 denotes an appropriate base upon which a metal plate 6 is secured, said base being provided with appropriate bearings 7 in which the opposite ends of a screw 8 are rotatably mounted. Between these bearings, 35 the plate 6 is formed with an opening 9 which is preferably rectangular, and the upper side of the base 5 may well be provided with a shallow recess 10 registering with said opening. Rigidly held in the opening 9 and recess 10, is an insulating base 11 which carries parallel contact tracks 12 and 13. The track 12 preferably consists of a single strip of metal snugly held in a groove 14 in the top of the base 11, while the track 13 consists of two slidably overlapped metal strips 15 and 16 whose overlapped portions are disposed in tight contact with each other, the base 11 being formed with grooves 15^a and 16^a which receive said strips respectively. By 45 this construction of the track 13, its length may be readily varied, by relatively sliding the strips 15 and 16. These strips may be held in adjusted position merely by frictional

contact with each other and with the walls of the grooves 15^a—16^a, or other provision could 55 be made for this purpose.

Wires 17 and 18 have been shown connected with the tracks 12 and 13 respectively, and a traveling contact has been shown, for bridging the gap between said tracks, so as to place 60 said wires in electrical communication with each other. The track-engaging portion of the traveling contact is denoted at 19, being in the form of a metallic member suitably guided in an inverted channel-shaped shell 20, which shell may be secured to an insulator 21, by appropriate fasteners 22. I have shown this insulator, secured to a traveling member 23, by screws 24, said member 23 being engaged with the screw 8. Thus, as this 65 screw is rotated in one direction by means forming no part of the present invention, the contact member 19 will move in one direction along the trackage 12—13 and will bridge the gap between the wires 17—18, while in engagement with both tracks. As soon however, as the member 19 leaves the end of the track 13, the wires 17—18 will have their electrical connection with each other broken. By 70 adjusting the track 13 to one length or another, the contact member 19 will remain in engagement with said track for a greater or a lesser time, as occasion may demand. Consequently, the length of time which the wires 75 17—18 shall be in electrical connection, may 80 be readily controlled.

The invention is rather simple and inexpensive, yet will be efficient, reliable and in every way desirable, for use with door-operating mechanisms or in other relations. As 85 excellent results are obtainable from the details disclosed, they may be followed if desired. However, within the scope of the invention as claimed, variations may be made.

I claim:—

1. In an electrical switch, a base, a contact strip thereon, a track on the base parallel with said strip, said track being formed of overlapping longitudinally-adjustable strips whose overlapping portions contact with each other, and a traveling contact shoe adapted to bridge between said strip and said tracks.
2. In an electrical switch, a pair of overlapping contact strips having their overlapping portions disposed in contact with each other, and a base having means for normally 100 105

holding said strips against sliding with respect to each other, said means however permitting such sliding when desired.

3. In an electrical switch, a pair of overlapping contact strips having their overlapped portions disposed in contact with each other, and a base having grooves in which said

strips are received for longitudinal adjustment, said strips frictionally engaging the walls of the grooves and being thereby held in adjusted position.

In testimony whereof I have hereunto affixed my signature.

CHARLES W. GORMAN.
